UNITED STATES PATENT OFFICE.

JOSEPH L. McCANN, JOHN P. McCANN, AND JAMES McCANN, OF BRIDGEPORT,
CONNECTICUT.

COLLAPSIBLE TENT-FRAME.

1,347,107.

Specification of Letters Patent. Patented July 20, 1920.

Application filed April 9, 1920. Serial No. 372,562.

To all whom it may concern:

Be it known that we, JOSEPH L. McCANN, JOHN P. McCANN, and JAMES McCANN, citizens of the United States, and residents 5 of Bridgeport, in the county of Fairfield and State of Connecticut, have invented certain new and useful Improvements in Collapsible Tent-Frames, of which the following is a specification.

10 This invention relates to new and useful improvements in collapsible tent frames and has for its object to provide a novel form of frame construction which may be made up from sheet metal sections that are adjust- 15 ably secured together to form a suitable frame over which a tent or other covering may be placed in a way to produce an in- closed building.

The further features of the invention are 20 to provide a series of collapsible sections that are adapted to be set up and connected one with another to form the complete frame; to design the main sections to include an adjustable post; braces and rafters that are 25 hinged and slidably connected together so that the same may be collapsed, closed and folded in a way to form a small bundle which will be light in weight and comparatively convenient to handle; to design these 30 several sections and parts so that the same may be inexpensively and strongly produced from sheet metal, such as galvanized iron, mostly in channel shapes; further to design the frame of a size and proportion which 35 when set up and covered with canvas will form a garage that can be used at night for sheltering an automobile and closed together and packed in the car during the day when traveling over the road.

40 With these and other objects in view the invention resides and consists in the construction and novel combination and arrangement of parts hereinafter more fully described, illustrated in the accompanying 45 drawings, and pointed out in the claims hereto appended, it being understood that various changes in the form, proportion, size and minor details of construction within the scope of the claims may be resorted to with- 50 out departure from the spirit or sacrificing any of the advantages of the invention.

Similar characters of reference denote like or corresponding parts throughout the several figures of the accompanying draw-

ings forming a part of this specification, and 55 upon which:

Figure 1 shows a front end view of our improved form of collapsible tent frame, the same being of a size and proportion adapt- 60 ed to accommodate an automobile.

Fig. 2 is a side view of the tent frame shown in Fig. 1.

Fig. 3 is an enlarged front elevation of the left hand corner post of the garage frame shown in Fig. 1, with a portion of the rafter 65 and brace therefore connected to the post.

Fig. 4 shows an inside view of the pivotal connection of upper post section and rafter including a thimble through which the pivotal bolt passes.

Fig. 5 is a side view of the post and attached brace and rafter shown in Figs. 2 and 3.

Fig. 6 shows a side view of one of the four corner posts with braces and rafter hinged 75 thereon, closed together to form a bundle ready for transportation.

Fig. 7 shows an enlarged cross section taken on line 7—7 of Fig. 6.

Fig. 8 is a similar cross section of the two 80 adjustably connected sections forming one of the posts, and

Fig. 9 shows a similar cross section of the telescopic ridge pieces which are supported 85 on the peak of the several rafters.

A tent frame of the size illustrated in the drawing for use as a garage would be best made to include six posts, four of which would constitute corner posts, and two intermediate posts. When knocked down 90 these same six posts with connected parts would be folded to form six comparatively small bundles which together with the other additional bundles including the ridge pieces and braces would comprise the outfit, and 95 when ready to carry would represent less than two hundred pounds in weight.

The four corner posts A and the intermediate parts B including their attached braces and rafters are alike in construction and therefore like reference characters will be applied to designate the corresponding parts of each. The intermediate posts are positioned in the sides opposite to each other and are in alinement with the corner posts. 100 These intermediate posts B are each provided with rafters and have two adjustable braces instead of one, as is the case with the 105

corner posts. All the posts are made of sheet metal, bent in the form of channel irons (see Figs. 7 and 8) and each include a lower upright section 10 having a broad flat outer face and the relatively narrow opposite parallel side portions 11, the longitudinal edges of which are bent in to form grooves 12 to receive and guide the edges 13 of the upper section 14. The lower end portion of the upper post sections are slidably mounted in the upper end portion of the lower section 10. These two members are adjustably secured together by means of a removable bolt 15 and wing nut 16 which bolt is positioned in holes formed in the two members and which are made to register at different specific distances apart, and whereby the height of the building is determined. A small angle iron 17 is riveted to the lower end of each of the bottom sections 10 and its bottom web portion is provided with a hole through which a bolt can be passed to engage the plate 18 which in practice is held in place by suitable pegs driven through holes thereof and into the ground.

The lower ends of the rafters 19 are hinged in the upper end portions of the top sections 11 by bolts 20 which also pass through a sleeve 21. The lower end portions of the rafters are positioned between the parallel sides of the said upper section 14 so that when the said rafter is folded down it will be contained wholly within the said upper section and thereby adapted to be slid with it into the longitudinal channel portion of the lower section 10 as indicated in Fig. 7. The upper adjoining end portions of the opposite pairs of rafters are secured together as indicated in Figs. 1 and 2 by a bolt 22 and on these several connected rafter ends are attached the connected adjustable ridge-pieces 23 and 24. The members 23 like the corner posts 10 are provided with turned in edge portions 25 to form guide-ways which hold and slidably support the adjoining section 24. These portions of the ridge-piece are secured together by bolts and nuts 26 similar to those employed for the corner posts. By this form of adjustable construction it will be readily seen that the corner posts may be set at variable distances from and with respect to the intermediate posts.

In addition to the foregoing we provide adjustable braces formed of two telescopic channel pieces 27 and 28, the upper piece of which is hinged to the lower section 10 of the posts as at 29 and the two sections extend inward and downward in alinement with the adjoining posts and the lower sections are provided with a flanged end portion 30 having a hole therethrough to receive a pin to be driven into the ground to hold the brace in position. These braces like the posts are made up of channel sec-

tions telescopically connected together and are secured by means of bolts 31 and wing nuts in the manner before explained.

The intermediate posts B are provided with two adjustable braces instead of one as is the case with the corner posts, the same being hinged to the opposite sides of the upper end portion of the lower section 10 and extend out in opposite directions in alinement with the corner posts and preferably so that their lower flanged end portions will engage with the flanged end portion of the adjoining braces.

We also provide small detachable braces for supporting the rafters, ridge pieces, side posts and general frame construction, which as will be seen from Figs. 1 and 3 include short pieces 32, one end of which is bolted to the upper sections 14 of the posts and the other end to the rafters 19. In addition to these two braces connected with opposite posts and rafters, we provide two aligned horizontal pieces 33, the outer ends of which are connected to opposite rafters, by the same bolts which connect the upper ends of the side braces. The inner ends of these horizontal braces are secured together by a bolt 34 which serves to connect the single upright 35 to the upper ends of the rafter by the before-mentioned bolt 22.

Having thus described our invention, what we claim and desire to secure by Letters Patent, is:

1. A collapsible supporting frame for tents comprising in part a series of foldable sections adapted to be connected together including a post formed of a bottom channel section having ways in its opposite side portions, a smaller channel piece adjustably connected to the lower section and adapted to slide into the lower section, and a rafter one end of which is hinged to the upper post section and adapted to be folded into the same.

2. A collapsible supporting frame for tents comprising a series of foldable sections adapted to be connected together including posts formed of a bottom channel section having ways in its opposite side portions, a smaller channel section adjustably connected to the lower section and adapted to slide into the lower section, a rafter one end of which is hinged to and adapted to be folded into the upper section of the post, and detachable braces extending from the post to the rafter and from one rafter to the other.

3. A collapsible supporting frame for tents comprising a series of foldable sections adapted to be connected together including posts formed of a bottom channel section having ways in its opposite portions, a smaller channel piece adjustably connected to the lower section and adapted to slide into the bottom section, a rafter the lower end of which is hinged to the upper post section

and the upper end to the end of the abutting rafter, adjustable braces hinged to the said posts and extending to the ground, and adjustable ridge pieces for rigidly connecting the top ends of the rafters.

4. A collapsible supporting frame for tents comprising a series of foldable sections adapted to be connected together including posts formed of a bottom channel section having ways in its opposite side portions, a smaller channel piece adjustably connected to each of the lower sections and adapted to slide into the said lower sections, rafters one end of each of which are

hinged to the upper post sections and the upper end to the end of an abutting rafter, and adjustable ridge pieces for rigidly connecting the pairs of rafters.

Signed at Bridgeport, in the county of Fairfield and State of Connecticut, this 30th 20 day of March, A. D. 1920.
